UNITED STATES PATENT OFFICE

149,012

DESIGN FOR A COMBINED TRICYCLE
AND TRAILERRalph E. Parker, Wichita, Kans., assignor to
J. Paul Carver, Wichita, Kans.

Application September 23, 1946, Serial No. 133,518

Term of patent 7 years

(Cl. D34—15)

To all whom it may concern:

Be it known that I, Ralph E. Parker, a citizen of the United States, residing at Wichita, in the county of Sedgwick and State of Kansas, have invented a new, original, and ornamental Design for a Combined Tricycle and Trailer, of which the following is a specification, reference being had to the accompanying drawing, forming a part thereof.

Fig. 1 is a perspective view of a combined tricycle and trailer, showing my new design; and

Fig. 2 is a top plan view thereof.

I claim:

The ornamental design for a combined tricycle and trailer, as shown.

RALPH E. PARKER.
